[57] CLAIM

The ornamental design for a toothbrush, as shown and described.

DESCRIPTION

FIG. 1 is a top plan view of a toothbrush showing our new design;
FIG. 2 is a right side elevational view thereof;
FIG. 3 is a bottom plan view thereof;
FIG. 4 is an elevational view as seen from the handle end thereof;
FIG. 5 is an elevational view as seen from the bristled end thereof;
FIG. 6 is a left side elevational view thereof;

FIG. 7 is an enlarged perspective view thereof;
FIG. 8 is a top plan view of a second embodiment of the design shown in FIG. 1;
FIG. 9 is a right side elevational view thereof;
FIG. 10 is a bottom plan view thereof;
FIG. 11 is an elevational view as seen from the handle end thereof;
FIG. 12 is an elevational view as seen from the bristled end thereof;
FIG. 13 is a left side elevational view thereof; and,
FIG. 14 is an enlarged perspective view thereof.
